UNITED STATES PATENT OFFICE.

DWIGHT W. WADSWORTH, OF FENNVILLE, MICHIGAN.

PACKING APPARATUS AND METHOD.

Application filed August 15, 1927. Serial No. 213,011.

The main objects of this invention are:

First, to provide an improved method of packing fruits and vegetables which greatly facilitates the packing of the fruit with a facing, that is, one or more layers of fruit arranged in a manner to present the best appearance when the container is opened.

Second, to provide an improved method for packing fruits and vegetables in barrels and the like which greatly expedites the work and enables the arrangement of a facing of the same in such a manner that they are not likely to be disturbed or displaced after the container is fully packed.

Third, to provide an apparatus for this purpose which is very economical in its parts and convenient to use.

Objects pertaining to details and economies of my invention will appear from the description to follow. The invention is defined in the claims.

A structure which embodies the features of my invention is clearly illustrated in the accompanying drawing, in which:

Fig. 1 is a side elevation of a portion of my improved apparatus, the facing supporting tray being removed from the standard.

Fig. 2 is an inverted perspective view of the facing supporting tray.

Fig. 3 is a perspective view of the collar-like facing holder which is in practice formed of paper or cardboard.

Fig. 4 is a fragmentary side elevation of the facing receptacle with the facing holder and a facing of fruit arranged therein.

Fig. 5 is a fragmentary side elevation of the parts shown in Fig. 4 with the supporting tray arranged upon the facing.

Fig. 6 is a fragmentary side elevation of the facing receptacle disposed in inverted position illustrating another step of the method.

Fig. 7 is a sectional view on line 7—7 of Fig. 8 illustrating the manner of engaging and disengaging the supporting tray with the tray supporting head.

Fig. 8 is a side elevation with the container shown in vertical section illustrating one step of my improved method.

Fig. 9 is a view of the parts shown in Fig. 8 illustrating still another step in the method.

Fig. 10 is a side elevation of parts of my improved apparatus illustrating still another step of my improved method.

Fig. 11 is a fragmentary side elevation of one of the receptacle rests.

Fig. 12 is an enlarged detail view partially in section on line 12—12 of Fig. 7, showing details of the supporting tray.

Referring to the drawing, the apparatus illustrated comprises a base 1 which is adapted to be secured to the floor or other suitable support provided with a socket adapted to receive the lower end of the standard 2, which in practice may be a piece of pipe. The standard 2 is provided with a pin 3 engaging a vertical slot 4 in the wall of the socket so that when the standard is engaged it is supported against rotation. The standard is provided with a triangular tray supporting head 5 having opposed notches 6 in the sides thereof, these notches being adapted to receive the studs 7 on the under side of the supporting tray 8. The supporting tray is engaged with the head by a sliding movement, the studs engaging in the recesses 6 properly locating the tray in a central position. The studs are provided with spring pressed collars 30 having spherically curved facings, these collars being yieldingly supported on the studs by means of the coiled springs 31—see the enlarged detail in Fig. 12. This avoids the need of great accuracy in manufacturing and the spring pressed collars yieldingly hold the tray 8 upon the head so that it is not likely to be accidentally dislodged.

On the standard 2 I mount a crosshead 9 for sliding adjustment. This crosshead is provided with radial arms 32 having receptacle supporting brackets 33 at their outer ends, these brackets having yieldingly supported rests 34 for the edge of a container 11, a barrel being illustrated in Figs. 8, 9 and 10. The brackets have upwardly projecting centering arms 35 which guide the receptacle to a central position, the rests being yieldingly supported by the springs 36 to compensate for staves of different lengths or a barrel that may be out of true, permitting the barrel being centered relative to the tray, the advantage of which will appear as the description proceeds.

Prior to arranging the barrel upon the support the top hoops are removed and the quarter hoop 12 is slipped up on the staves allowing the open end of the barrel to expand. The crosshead is slidably supported on the standard, a ring clutch 13 being pivotally mounted at 14 on the link 15. The spring 16 urges the clutch to engaging position. A set screw 17 is provided for adjusting the tension of the spring. The clutch is provided with a hand

hold 18 so that an upward lift on the hand hold will release the clutch.

While the clutch 13 is sufficient to support the crosshead with the container arranged thereon, its friction engagement is adjusted so that by a downward pressure on the barrel the crosshead may be moved to the position shown in Fig. 9 without releasing the clutch.

In Figs. 8, 9 and 10 I have illustrated the preliminary steps of packing the container, that is, the supporting of a facing of the articles to be packed upon the tray so that the container may be inverted over this facing and adjusted to position the facing in the bottom of the container or at the end of the container, which becomes the top when the same is opened for display purposes or to remove the contents.

To support the facing and to facilitate the arrangement thereof I provide a collar-like facing holder 19 for each container packed. This holder 19 is arranged in a pan-like facing receptacle 20 and one or more layers of the articles to be packed, indicated at 21, is arranged therein as illustrated in Fig. 4. The supporting tray 8 is then arranged within the facing receptacle, as illustrated in Fig. 5, upon the facing and the receptacle with the tray therein inverted as shown in Fig. 6. To facilitate this the receptacle is provided with hand holds 23 while the tray is provided with grips 24 which may be positioned relative to the hand hold so that the tray may be held firmly upon the facing as the facing receptacle is inverted.

To adapt the apparatus for fruits or vegetables of smaller size the tray is provided with another pair of hand holds 25 which may be grasped in the event that when the tray is inserted as a follower it enters further into the receptacle than shown in Fig. 5.

With the parts assembled as shown in Fig. 6, the assembly is placed upon a table or other supporting surface with the ends of the hand hold supports 37 projecting to constitute legs resting on the support. The receptacle 20 is then removed, leaving the supporting tray with a facing holder and facing arranged therein, as shown in Fig. 8. By means of the handles 25 the tray is then mounted on the head 5 of the standard. This method releases the facing receptacle so that another facing unit may be "set up" by another worker.

The container 11 is then arranged in inverted position on the cross head as shown in Fig. 8 and pushed down to the position shown in Fig. 9. The standard is then lifted from the base and the container inverted, as shown in Fig. 10, the standard and tray being lifted out as indicated by dotted lines in Fig. 10, leaving the facing with the facing holder collar in the container so that the container may be completely filled and closed.

By this apparatus and method I am able to very rapidly pack fruits and vegetables,

facing the same in an attractive manner and without injury thereto.

I have illustrated and described my improvements in an embodiment which I have found very practical. I have not attempted to illustrate or describe other adaptations or modifications which I contemplate as I believe the disclosure made will enable those skilled in the art to embody or adapt my improvements as may be desired.

Having thus described my invention what I claim as new and desire to secure by Letters Patent is:

1. In an apparatus of the class described, the combination of a standard provided with a triangular tray supporting head having opposed notches therein, a container supporting crosshead slidable on said standard and provided with a friction clutch, said crosshead being provided with container centering shoulders, a facing supporting tray provided with headed studs on its under side engageable in the notches of the tray supporting head whereby the tray is detachably connected thereto, a collar-like facing holder, and a facing receptacle adapted to receive said facing holder and tray and to be inverted therewith, for the purpose specified.

2. In an apparatus of the class described, the combination of a standard provided with a triangular tray supporting head having opposed notches therein, a container supporting crosshead slidable on said standard and provided with a friction clutch, said crosshead being provided with container centering shoulders, and a facing supporting tray provided with headed studs on its under side engageable in the notches of the tray supporting head whereby the tray is detachably connected thereto.

3. In an apparatus of the class described, the combination of a base, a standard detachably engageable with said base and provided with a tray supporting head, a container supporting cross head adjustably mounted on said standard, a facing supporting tray engageable with said head, a collar-like conical facing holder adapted to embrace said tray to be supported thereby, and a facing receptacle adapted to receive said facing holder and tray and to be inverted therewith, for the purpose specified.

4. In an apparatus of the class described, the combination of a base, a standard detachably engageable with said base and provided with a tray supporting head, a container supporting crosshead adjustably mounted on said standard, and a facing supporting tray engageable with said head.

5. In an apparatus of the class described, the combination of a standard provided with a tray supporting head, a container supporting cross head adjustably mounted on said standard, a facing supporting tray engageable with said head, a collar-like conical fac-

ing holder adapted to embrace said tray to be supported thereby, and a facing receptacle adapted to receive said facing holder and tray and to be inverted therewith, for the purpose 5 specified.

6. In an apparatus of the class described, the combination of a standard provided with a tray supporting head, a container supporting cross head adjustably mounted on said 10 standard, and a facing supporting tray slidably engageable with said head with a transverse movement.

7. In an apparatus of the class described, the combination of a standard provided with 15 a tray supporting head, a container supporting crosshead adjustable on said standard, a facing supporting tray detachably engageable with said head, a collar-like facing holder, and a facing receptacle adapted to receive 20 said facing holder and tray.

8. In an apparatus of the class described, the combination of a standard provided with a supporting head, a container supporting crosshead adjustably mounted on said standard, 25 said crosshead having radial arms provided with receptacle supporting brackets at their outer ends, said brackets having upwardly projecting arms and yieldably receptacle supporting rests disposed at the side of 30 said arms, and a facing supporting tray engageable with said head.

9. In an apparatus of the class described, the combination of a standard provided with a facing supporting means, and a container 35 supporting crosshead adjustably mounted on said standard and provided with yieldable receptacle rests.

10. In an apparatus of the class described, the combination of a standard provided with 40 a facing supporting head, and a container support slidably mounted on said standard and adapted to support a receptacle in inverted position, said container support having yieldable receptacle rests for facilitating the 45 centering of the receptacle with said facing supporting means.

11. The method of packing consisting of disposing a collar-like tapered holder within

a receptacle and arranging a facing of the articles to be packed therein, placing a supporting tray upon such facing and inverting and removing the receptacle, leaving the facing holder on the tray with the facing therein, inverting a container over the said facing holder and tray, turning the container to upright 55 position while the facing is supported by the tray and facing holder, removing the tray, and completing the packing of the container.

12. The method of packing consisting of disposing a collar-like facing holder within 60 a receptacle and arranging a facing of the articles to be packed therein, placing a supporting tray upon such facing and inverting and removing the receptacle leaving the facing holder on the tray with the facing therein, inverting a container over the said facing holder and tray, reversing the container and removing the tray leaving the facing holder in the container.

13. The method of packing consisting of 70 disposing a collar-like holder within a receptacle and arranging a facing of the articles to be packed therein, placing a facing retaining member upon such facing and inverting and removing the receptacle leaving the facing 75 supported by said holder upon said retaining member, inverting a container over the said facing holder and retaining member, and reversing the container.

14. The method of packing consisting of 80 disposing a collar-like holder within a receptacle of a sectional dimension approximately that of the final container, arranging a facing of the article to be packed therein, arranging a facing retainer member upon such 85 facing, inverting the receptacle and facing retainer as a unit, removing the receptacle and inverting a container over the said facing holder and its said facing retainer member while they are in assembled relation, reversing the container, and removing said facing retainer.

In witness whereof I have hereunto set my hand.

DWIGHT W. WADSWORTH.
